(57) **CLAIM**

The ornamental design for a ventilated pet carrier backpack, as shown and described.

DESCRIPTION

FIG. 1 is a front perspective view of the ventilated pet carrier backpack, showing my new design;
 FIG. 2 is a rear perspective view thereof;
 FIG. 3 is a front elevation view thereof;
 FIG. 4 is a rear elevation view thereof;
 FIG. 5 is a right side elevation view thereof;
 FIG. 6 is a left side elevation view thereof;
 FIG. 7 is a top plan view thereof; and,
 FIG. 8 is a bottom plan view thereof.
 The broken lines depict portions of ventilated pet carrier backpack that do not form part of the claimed design.

1 Claim, 8 Drawing Sheets(56)
